(57) **CLAIM**

The ornamental design for a hybrid endodontic file, as shown and described.

DESCRIPTION

FIG. 1 is a perspective view of the hybrid endodontic file; FIG. 2 is a left side elevational view of the hybrid endodontic file, with the right side being a mirror image thereof; FIG. 3 is an elevational view of the proximal end of the hybrid endodontic file;

FIG. 4 is a cross sectional view of the hybrid endodontic file, taken along lines 4-4 in FIG. 2; and,

FIG. 5 is a cross sectional view of the hybrid endodontic file, taken along lines 5-5 in FIG. 2.

The broken lines in the figures are included for the purpose of illustrating portions of the hybrid endodontic file that form no part of the claimed design.
